UNITED STATES PATENT OFFICE.

JAMES COULTER, OF BRIDGEPORT, CONNECTICUT.

AUTOMATIC SCREW-CUTTING AND TURNING LATHE.

No. 908,960.

Specification of Letters Patent.

Patented Jan. 5, 1909.

Application filed April 4, 1905. Serial No. 253,764.

To all whom it may concern:

Be it known that I, JAMES COULTER, a citizen of the United States, and a resident of Bridgeport, in the county of Fairfield and

5 State of Connecticut, have invented certain new and useful Improvements in Automatic Screw-Cutting and Turning Lathes, of which the following is a specification.

My invention relates to automatic screw cutting and turning lathes, and is an improvement on the patent granted to me February 14th 1905 #782,220 and it consists, while running the lathe spindle and feed screw continuously in one direction, in utilizing 10 the reversing-shaft for automatically disengaging the feed-nut from the feed or lead screw at the same time that the cutting-tools are withdrawn; and thus leave the carriage free to be instantly returned to the starting 15 point by means of a weight, and to automatically reengage the feed-nut with the feed-screw at the same time that the cutting-tools are reengaged with the work at such starting point; thus greatly shortening the 20 operation of cutting threads or turning work, and thereby materially cheapening the product over the present method of running the carriage back by means of the feed-screw.

25 30 To enable others to understand my invention, reference is had to the accompanying drawings in which:

Figure 1—is a rear elevation of the lathe: Fig. 2—is a broken sectional view of the lathe, bed, and cross sectional view of the feed-screw and reversing-shaft through line a a of Fig. 1; also broken view of the carriage showing the cams on the reversing-shaft for operating the tool-holders: Fig. 3—is a cross sectional view of the feed-screw and reversing-shaft, and detail side elevation of the slide adapted to carry one of the tool-holders, and the feed-nut to engage with the feed-screw: Fig. 4—is a 35 broken view of the feed-screw and upper plan view of its traveling support, and an upper plan view of the feed-nut: Fig. 5—is a broken view of the reversing-shaft broken view of one of the tool-holder sup-

40 45 50 55 ports showing its connection with one of the cams on the reversing-shaft, and broken view of the sliding-bar that operates the other tool-holder: Fig. 6—is an enlarged broken view of the head-stock and a cross sectional view of the reversing-shaft through line b b of Fig. 1, showing the escapement

mechanism with the reversing-shaft: Fig. 7—is a broken view of the reversing-shaft and head-stock looking in the direction of arrow c of Fig. 6.

60 A brief description of the old features of the lathe will assist very materially in understanding the improvements added thereto. These old features comprise the bed 1 on which is mounted the traveling carriage 65 2. 3 and 4 are slides mounted on the carriage carrying the tool-holders 5 and 6. 7 and 8 are the cutting-tools. The tool-holders 5 and 6 are moved on said slides to and from the work 9 by means of the shaft 10 70 having the right and left hand threaded portions 10^a and 10^b operating in threaded holes of the lugs 11 and 12. This shaft is operated either by hand or automatically through the medium of the handles 13. As 75 the means for operating this shaft are fully explained in my former patent, a detail description is unnecessary here.

14 is the reversing-shaft having the two cams 15 and 16, one to engage the uprights 80 17 of the sliding-bar 18, to which the tool-holder slide 3 is secured by the screws 19, as shown at Fig. 2, and the cam 16 to engage with the steel pieces 20 of the slide 4, shown more clearly at Fig. 5, so that, by means of 85 these cams, the slides and tool-holders are automatically moved to and from the work. There is a continuous rotary tension on the reversing-shaft 14 imparted thereto by means of a friction device located within 90 the casing 21, Fig. 1. The rotary movement of the shaft 14 is temporarily checked by the escapement mechanism comprising, see also Figs. 6 and 7, the collar 22 secured to said shaft, which collar has the lip 23 95 adapted to alternately engage with the stop 24, secured to the head-stock of the lathe, and the stop 25 also secured to said head-stock.

26 and 27 are collars adjustably mounted 100 on the reversing-shaft and they are adapted to be set to represent the travel of the lathe carriage in either direction so that, when feeding forward, the carriage will engage the collar 27 and move the reversing-shaft 105 in the same direction, and thereby disengage the collar 22 from the stop 24, and, when so disengaged, the friction device will partially rotate said shaft to bring the lip 23 of said collar into engagement with the other stop 110 25. During this partial rotation of the reversing-shaft, the cams 15 and 16 will have

moved the slides 3 and 4, and also their tool-holders in opposite direction to withdraw the cutting-tools from the work as shown at Fig. 1, and when the carriage, on its 5 return, engages the collar 26, the tools are reengaged with the work.

In my former construction, the lathe spindle and feed-screw were reversed, but in my present construction the lathe spindle

10 and feed-screw run continuously in one direction, and the carriage is automatically brought into engagement with the feed-screw and disengaged therefrom in the manner presently to be explained. The lathe-spindle 15 28 carries the pinion 29 to mesh with the gear 30 on the reversing-shaft, and this gear, or an intermediate thereof, as the case may be, to mesh with the pinion 31 on the feed-screw 32. The necessary motion is imparted 20 to these parts through the medium of the cone pulleys 33 on the lathe-spindle.

34, Fig. 2, is a bracket secured to the underside of the lathe-carriage having the head portion 34^a adapted to embrace and support 25 the feed-screw 32. 35, see also Figs. 3 and 4, is another bracket secured to the underside of the slide 18, and 36 is a half nut secured to the lower end of the said bracket by the screw 37. This nut is adapted to be engaged 30 with and disengaged from the feed-screw as follows: 38, Fig. 1, is a chain attached to the lathe-carriage, and, running over the pulley 39, carries at its free end the weight 40. When, therefore, the forward movement 35 of the carriage engages the collar 27 on the reversing-shaft and causes the slides 3 and 4 to move outward, as before mentioned, the feed-nut 36 will, of course, be carried back by the slide 18 to disengage the 40 carriage from the feed-screw; this will bring the carriage entirely under the control of the weight 40 so that, the moment the feed-nut is withdrawn from the feed-screw, the weight will instantly return the carriage, 45 and, as soon as it strikes the collar 26 of the reversing-shaft, the feed-nut and feed-screw are reengaged on the return movement of the slide 18. To prevent a jar or shock when the carriage is brought suddenly in contact 50 with the collar 26, I provide an air cushion on the reversing-shaft, which cushion is represented by the cylinder 41. As the means for forming this air cushion are well known, it is not necessary to enter into a 55 detail description of its construction.

In cutting left hand threads, the feed-screw is reversed in the usual manner, by means of intermediate gears, and the weight 40 is transferred to the chain 42, leading 60 from the opposite side of the carriage and over the pulley 43, and the weight 44 on this

chain will be transferred to the chain 38. This latter weight is intended only to take up the slack in the chain not used by the heavy or carriage returning weight. 65

While I show front and rear tool-posts in operation, it will be understood that there are times when only the front one is required, in which case, the rear one can be removed. 70

In my former construction, there were many more parts connected with the lathe than are required in the present and improved construction, and, too, it was very much slower in its operation. In order to 75 return the carriage, both the lathe, spindle and feed-screw had to be reversed, and the carriage was returned entirely by the feed-screw. In my present construction, the lathe spindle, as before mentioned, and feed-screw run continuously in one direction so that, by throwing out the feed-nut at the same time that the cutting-tools are thrown out, and returning the carriage by means of a weight, I avoid the delay caused by running the carriage back by the slow working process of the feed-screw. 80 85

Having thus described my invention what I claim as new and desire to secure by Letters Patent is: 90

1. In an automatic machine of the character described, the combination with a traveling carriage, a tool-holder thereon, a shaft for actuating said holder to and from the work, of a continuously running spindle and feed-screw, a reversing shaft, a feed-nut carried by the carriage and adapted for engagement and disengagement with the feed-screw, means connected with the reversing shaft for actuating said feed-nut, and a weight for 95 returning said carriage when the feed-nut is out of engagement with the feed-screw, for the purpose set forth.

2. In an automatic machine of the character described, the combination with a traveling carriage, a tool-holder thereon, a shaft for actuating said holder to and from the work, of a continuously running spindle and a feed-screw, a reversing shaft, a feed-nut carried by the carriage and adapted for engagement and disengagement with the feed-screw, means connected with the reversing shaft for actuating said feed-nut, for the purpose set forth. 100 105

Signed at Bridgeport, in the county of 115 Fairfield and State of Connecticut, this 2d day of Mar. A. D. 1905.

JAMES COULTER.
